UNITED STATES PATENT OFFICE.

EDWARD E. CLEMENT, OF WASHINGTON, DISTRICT OF COLUMBIA.

TELEPHONE-EXCHANGE SYSTEM.

1,023,480.

Specification of Letters Patent.

Patented Apr. 16, 1912.

Application filed August 3, 1906. Serial No. 329,114.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems, and particularly to semi-automatic systems.

It has for its object to enable an operator to make connections in such systems with 15 certainty and ease as well as celerity, at the same time making a permanent record thereof which may be used for other purposes.

Briefly outlined, my present invention 20 comprises an operator's sending machine or controller for automatic switches or equivalent devices having as its distinguishing characteristic feature a set of punches by which perforations are produced in a paper 25 roll or card corresponding in their arrangement to the number or connection desired. This paper or card is fed under contact springs after being punched and by making and breaking the contacts between these 30 springs and a platen sends the proper impulses of current through the controlling circuits to produce the desired result.

My invention is illustrated in the accompanying drawings, wherein—

35 Figure 1 and Fig. 2 are connected diagrams showing in its entirety a talking connection at a central office. Figs. 3 and 4 are connected diagrams showing the operator's sender and circuits. Fig. 5 is a detail section of a portion of the sender.

40 Referring to the drawings, I will first briefly describe Figs. 1 and 2, since these show a conventional type of circuits and apparatus which in itself forms no part of the present invention, except as to those 45 parts of the cord circuit which are designed to connect with the improved operator's circuits.

In Fig. 1, A is a subscriber's station, 50 fitted with the usual common battery telephone set. From this substation line wires 1 and 2 lead to the central office, terminating on the contacts of a cut-off relay N, normally connecting them to the line signal

relay N and battery on one side and to 55 ground on the other. Line extensions 3 and 4 go to the answering jack J, and are multiplied at 5 and 6 to the calling or connecting terminals *j* in the switch banks of the automatic switches to which I shall presently 60 refer.

J' is a multiple terminal of the trunk 19—20 leading to a selector switch S, of the type shown in Letters Patent 815,321, to Keith and Erickson, dated March 13, 1906. 65 This jack and its multiples all have triple contacts, the sleeve or test thimble being grounded through a proper resistance for both test and control purposes. The selector switch coats in making connections, 70 with a number of connector switches, one of which is indicated at S' in Fig. 2. This is of the type shown in Letters Patent 815,176, to Keith and Erickson, March 13, 1906. By means of the double set of switches thus indicated in the drawing, selection may be made of any one of a thousand subscribers 75 and his line connected with the calling line. I have not deemed it necessary to show more than this, although the addition of one 80 more selector switch would carry the system to ten thousand. Such extension is well understood in the art and is within the skill of any well informed automatic telephone engineer.

To contact the jack J of any calling line with the jack J' of a trunk to a selector switch, I provide operators' plugs P—P', in pairs connected by the conductors 9—17, 10—18, the cords being conductively severed 90 by the condensers shown. Bridged across the answering end, 9—10, of each cord are the relays R, R', with the main battery B between them. That is the sleeve relay R' is connected from conductor 10 to battery wire 7, while the tip relay R is connected from the conductor 9 to ground. As the positive side of the battery is grounded this bridges the battery. This connection enables current to be supplied for both talking and signaling over the subscriber's line, and also to the cut-off relay N' over a portion of the talking circuit.

The operator's telephone set is shown at O, having a triple wound induction coil, the upper coil or secondary being bridged across the cord conductors 9—10 by relay R² when the answering plug is inserted in a jack,

the primary or middle coil going to the transmitter circuit, and the lower or tertiary coil being connected by relay R^4 for test, to the tip of the calling plug P' , under normal conditions of disuse.

I will now pass to Figs. 3, 4, and 5. Fig. 4 shows the punching apparatus and paper roll or tape, while Fig. 3 shows the circuits and apparatus whereby this roll when punched is made to affect the switches through the cord circuit of Fig. 1. Referring first to Fig. 4, C indicates the paper working mechanism, comprising the punches c^2 , normally pressed upwardly by springs; the supporting plate c^3 for them; the die-plate c^1 having holes beneath all the punches and supporting the paper c as it comes from the roll C' ; the contact springs c^5 c^6 c^7 , secured to but insulated from the platen c^8 and normally tending to touch the same to complete their respective circuits; and suitable supporting means for all these, not shown. These figures of necessity are diagrammatic in their character, but all the mechanical connections not forming part of the invention are presupposed in this description. In Fig. 3 the paper c is shown coming from the platen c^8 and passing over a feed roll C^2 , having friction rolls c^4 . This feed roll may be driven in any suitable manner, but is shown as connected through a shaft on the dotted line m^3 to the electric motor M , which also carries the commutator disk m for cut-off purposes. Instead of this electric motor for each paper outfit, where there are several operators, I contemplate the employment of one motor with clutches for the rolls C^2 and disks m , controlled by electromagnets in the circuits 32, 34, of the motor M , each clutch controlled by its own disk m , but the one motor running constantly or as long as any paper mechanism is in use.

Passing up from the cord conductors 17—18 of Fig. 1 are two wires 15—16 which I may call the rotary and the vertical wires, since they carry the current impulses usually so called in the automatic art. These wires are controlled as to their continuity jointly by the key K and the relay R^7 , and separately by the relays R^4 and R^5 . Wire 15 passes to contacts of relay R^7 , from which wire 21 passes to contacts of relay R^5 , from which wire 27 passes to battery. Wire 16 passes to contacts of relay R^7 , from which wire 22 passes to contacts of relay R^4 , from which wire 24 passes to the middle spring c^1 , of Fig. 4.

Relay R^4 is connected by wire 25 to the spring c^6 of Fig. 4. Relay R^5 is connected by wire 23 to the spring c^5 . Each of these relays is directly controlled by the paper and springs, therefore.

C^3 is a starting button for the operator.

It is associated with the buttons c^2 of the punch set, although it is shown in Fig. 3. This button C^3 when depressed energizes the starting relay R^6 to close the motor circuit, this relay thereafter remaining energized through the disk m until the latter has made one revolution. A lamp is associated with this button to indicate to the operator that the transmitter is in use, and to show when it again becomes free. The lamp takes current from the disk m during the single revolution referred to.

In order to permit the operator to correct a mistake, and to punch the correct number before transmitting, I provide the disabling or dummy starting key C^4 . This closes the motor circuit, and that of the relay R^7 , which breaks both wires 15 and 16, so that for one revolution the paper c is drawn forward but no impulses get upon the wires. A guard lamp is also provided for this button or key, being preferably a red lamp on the same circuit as the relay R^7 , so that it will burn while the false length of tape is being drawn forward, and will then go out.

Before giving the operation of this system, I should explain that only five punches c^2 are shown in each set, and three sets. In a full operative machine there are ten punches in each set, and there are as many sets as there are digits or separate numerals to be called. Thus to call up to one thousand, nine, nine, nine, is the limit, for which three sets of ten punches each are sufficient. To call up to ten thousand, nine, nine, nine, nine, is the limit, and if selective ringing is to be practiced I may use an additional set for that. With the outfit actually as shown in Fig. 4 the highest number that can be punched is five, five, five. I have thus reduced the number of buttons to simplify the drawing.

In operation, suppose the subscriber A calls by taking down his receiver: line lamp n lights, the operator plugs in with P , and relays R^4 and R^5 pull up, with the cut-off relay N' . The line is then on the cord conductors 9—10 and through wires 11—12 to circuit 8 of the operator's telephone O . Having ascertained the number wanted, and that it can be reached, we will assume, through the trunk 19—20, the operator tests the jack J' with the tip of her plug P' , and finding it idle, plugs in. Relay R^3 pulls up, cutting off relay R^2 , which cuts off the operator's telephone from the answering cord 9—10, and at the same time cutting off the tertiary or test winding from the tip conductor 17. The operator then depresses the two-step-escapement key K to connect her wires 15—16 to the cord, and sets up the number by pressing down the appropriate punches c^2 . As shown in Fig. 4, the number

punched is 431. If this is the right number, the operator then pushes down the button C³ of Fig. 3, which closes the circuit of the relay R⁶ as follows: B—27—35—30—31—5 R⁶— and ground to B. The relay pulls up, closing the motor circuit as follows: B—32—34—33—B. The motor then starts to turn and turns with it the shaft m² and the feed roll C² as well as the disk m. The latter at 10 once takes control of the circuit of relay R⁶ as follows: B—27—28—m—m'—29—31—R⁶—B. The operator may then release the key C³ which is only required to close the circuit of relay R⁶ long enough to start the 15 motor. This continues for one revolution of m, during which the feed roll C² is supposed to draw the paper tape c forward enough to pass the three sets of perforations already prepared, under the springs c⁵—c⁶—20 c⁷. As the middle set, c¹⁰, pass under pen c⁷, they permit the latter to touch the platen at intervals, closing the following circuit: B—40—c⁸—c⁷—24—22—16—17 (Fig. 1)—P'—J'—19— and so to the vertical relay 25 of switch S and to ground, back to battery. As soon as four of these impulses have been transmitted over the path traced, the hole c¹¹ comes under the pen c⁸, closing the following circuit: B—40—c⁸—c⁶—25—R⁴—30 ground to B. R⁴ thereupon pulls up promptly before another impulse comes on wire 16, and disconnects the wires 22 and 24, at the same time locking itself through the back contact of relay R⁶. Only four 35 impulses can go over wire 16, therefore, until this locking circuit is unlocked, and the switch S of Fig. 2 is therefore stepped up to the fourth row of contacts j' j² and stops there. As the paper tape passes on, the hole 40 c⁹ finally comes under spring pen c⁵, and closes the following circuit: B—40—c⁸—c⁵—23—R⁵— and ground to B. R⁵, pulls up its armature, breaks the locking circuit of relay R⁴, which thereupon lets go its armature, 45 and at the same time a rotary impulse is sent to wire 15 as follows: B (Fig. 3)—27—21—15—18 (Fig. 1)—P'—J'—20— and so to the rotary relay in switch S of Fig. 2, which thereupon steps around the side 50 switch one step and shifts the control of the switch from the vertical to the rotary magnet, preparing the switch for rotary movement, which is automatically made to find a trunk. The relay R⁴ now being back, the 55 impulses from spring c⁷ come again onto wire 16 and to the trunk wire 19, affecting the vertical relay of the switch S', whose trunk has been selected as idle by switch S. This is a connector switch, and its spindle s 60 goes up to the desired row, which is the third, since the hole c¹¹ punched in the second set on the tape is just after the third of the holes c¹⁰. As soon as hole c⁸ reaches the spring pen c⁵, relay R⁵ is pulled up, as before, and a rotary impulse comes on wire 65 15. This impulse passes all the way to switch S', and works its rotary relay, which shifts the side switch and puts on the rotary magnet so that the last set of impulses will select the contact wanted in the row already selected. The same rotary impulse by energizing relay R⁵ again unlocks R⁴ and prepares for the last set of impulses. These 70 come in order and in the same manner as those already described. It happens that 75 the number is one, and this steps the arms s² of the switch S' around to the first contact in the third row, which is connected to line 431, desired. The hole c¹¹ of the last set again has locked relay R⁴ and has cut off 80 the wire 16; and the last rotary impulse coming through hole c⁹ again energizes relay R⁵ to unlock relay R⁴. The passing of the last hole c⁹ of the set completes the transmitting cycle and at that time the disk m 85 comes to the end of its revolution, the spring pen m' passes onto the insulating spot m², the circuit of the motor M is thus broken by relay R⁶, and the paper and all come to a 90 rest. The lamp associated with key C³ 95 glows by reason of current in the following circuit: B—27—28—m—m'—29—30—lamp—ground to B. When disk m breaks this circuit the lamp goes out.

When current first comes on wire 29 it 95 passes to wire 39 and so to the magnet of the key K, which takes one step by swinging its armature lever so as to let the button move up half way. When the disk m finally breaks the circuit to the battery for the wire 100 29, the magnet of the key loses current and the button takes the second half of its step so as to cut off the operator's sending circuit 15—16 from the cord entirely. The same circuit 15—16 may thus extend to a number 105 of cord circuits, having a key K for each. The time of sending three sets of impulses as described is only about three seconds, or four sets in four seconds. The key C⁴ is 110 never depressed except when a wrong number 115 has been punched.

While this application relates primarily to a telephone system, in which the actuating impulses for automatic switches are sent by means of the sending device herein described, it is obvious that the same sending device might be used advantageously for other purposes. I wish it understood therefore that I contemplate any use of this sending device which is equivalent to that described herein, and which falls fairly within the scope of the appended claims.

Having thus described my invention, what I claim and desire to secure by Letters Patent is:

1. In a telephone exchange system, a plurality of lines to be connected, central office automatic switching apparatus for connect-

- ing the same, a body containing a permanent set of perforations adapted to work the switching apparatus to the highest number possible of selection, and means for producing modifying perforations in said body corresponding with any particular number wanted, substantially as described. 5
2. In a telephone system, the combination of automatic switching apparatus and controlling means comprising a body partially perforated for selective purposes, means controllable by an operator to complete the perforations to select any desired number, contacts controllable by the perforated body 10 and connected in the switching circuits, and a motor for producing relative motion between the body and contacts, substantially as described. 15
3. In a telephone exchange system, line circuits terminating at a central office, automatic switching apparatus at the central office for interconnecting the lines, and controlling apparatus for the switches also at the central office and comprising the following 20 instrumentalities: a perforated body, co-operating contacts and a suitable motor for producing relative motion therebetween, and means controlled by an operator for varying the perforations in the body in accordance 25 with the number to be selected, substantially as described. 30
4. In a telephone system, a plurality of telephone lines to be connected, automatic switches for connecting said lines, and controlling means for said automatic switches comprising contact devices and a perforated tape, together with punching means controlled by an operator for modifying the perforations in the tape according to the 35 number to be selected, substantially as described. 40
5. In a telephone system, a plurality of telephone lines to be connected, automatic switches for connecting said lines, controlling 45 means for said automatic switches comprising contact devices and a perforated tape, a locking key for connecting said controlling means to said switches, and automatic unlocking means for said key. 50
6. In a telephone system, a plurality of telephone lines to be connected, automatic switches for connecting said lines, controlling means for said automatic switches comprising contact devices and a perforated tape, 55 and means for connecting said controlling means to said automatic switches during the interval required to control the automatic switches to connect with a desired line. 60
7. In a telephone system, a plurality of telephone lines to be connected, automatic switches for connecting said lines, and requiring a plurality of complete transmitted signals of control to effect the connection of a calling line with a selected line, a tape 65 perforated in consecutive digital signal- 65 units, and means for transmitting impulses through the perforations of said tape to said automatic switches in required groups of signal-units, each corresponding to one digit of the complete number. 70
8. In a telephone system, a plurality of telephone lines to be connected, automatic switches for connecting said lines, and requiring a plurality of complete transmitted signals of control to effect the connection of a calling line with a selected line, controlling means for said automatic switches consisting of a contact-making device and a control tape perforated in consecutive digital signal-units, and further means for passing said tape through said contact-making device intermittently in steps, each step comprising a group of signal-units, and each adapted to produce one step of the automatic switches to select one digit of the complete number 80 wanted. 85
9. In a telephone exchange system, a plurality of lines to be connected, a plurality of automatic switches for interconnecting them, and controlling means for the switches comprising the following instrumentalities: contacts connected to the switches, a platen common to said contacts, a paper tape and a motor adapted to feed the same over the platen and under the contacts, and a set of operator's keys adapted when depressed to produce perforations in the tape corresponding to the numbers to be selected, together with means controlled by the operator for starting the motor mechanism and consequent movement of the tape under the contacts, whereby a number may be set up or punched and the switches thereafter caused to select the corresponding line, substantially as described. 90 95
10. In a telephone exchange system, a plurality of lines to be connected, a plurality of automatic switches for connecting them, and controlling means for the switches comprising the following instrumentalities: contacts, a paper tape and motor mechanism adapted to feed the same under the contacts, operator's selective punches for perforating the tape in accordance with the number to be selected, and means for connecting said contacts to the switch circuits when a connection is to be made, and for disconnecting the contacts therefrom when a connection is completed, substantially as described. 100 105
11. In a telephone exchange system, a plurality of lines to be connected, a plurality of automatic switches for connecting them, and controlling means for the switches comprising the following instrumentalities: contacts, a paper tape and motor mechanism adapted to feed the same under the contacts, operator's selective punches for perforating the tape in accordance with the number to be 110 115 120 125

selected, means for connecting the tape to operate the switches, and means for automatically disconnecting the same after the line connection has been established by the switches substantially as described.

12. An electrical system of intercommunication comprising a plurality of lines, automatic switches for interconnecting the same, and controlling means for the switches comprising a perforated tape, contacts con-

trolled thereby, and means for bringing said contacts into temporary connection with the switches when the same are to be actuated, substantially as described.

In testimony whereof I affix my signature ¹⁵ in presence of two witnesses.

EDWARD E. CLEMENT.
